UNITED STATES PATENT OFFICE.

JOHN ROGERS FLANNERY AND ETHAN I. DODDS, OF PITTSBURGH, PENNSYLVANIA,
ASSIGNORS TO FLANNERY BOLT COMPANY, OF PITTSBURGH, PENNSYLVANIA.

STAY-BOLT STRUCTURE.

1,295,883.

Specification of Letters Patent.

Patented Mar. 4, 1919.

Application filed May 3, 1918. Serial No. 232,304.

To all whom it may concern:

Be it known, that we, JOHN R. FLANNERY and ETHAN I. DODDS, citizens of the United States, and residents of Pittsburgh, in the county of Allegheny and State of Pennsylvania, have invented certain new and useful Improvements in Stay-Bolt Structures; and we do hereby declare the following to be a full, clear, and exact description of the invention, such as will enable others skilled in the art to which it appertains to make and use the same.

This invention relates to improvements in staybolt structures and more particularly to means for closing the end of the bearing of the head of the staybolt,— the object of the invention being to provide simple means whereby a closure may be secured in place over the head of the bolt and to so construct said closure and its fastening means that the same may be quickly removed and as quickly replaced in facilitating examination of the staybolt for testing purposes.

With this and other objects in view, the invention consists in certain novel features of construction and combinations of parts as hereinafter set forth and pointed out in the claims.

In the accompanying drawings, Figure 1 is a longitudinal sectional view showing an embodiment of our invention. Fig. 2 is a transverse section on the line 2—2 of Fig. 1, and Fig. 3 is a separate view of the cap or closure.

1 represents a bearing sleeve adapted for connection with a boiler sheet and having therein a curved face 2 constituting a bearing for the head 3 of a staybolt 4. The bearing sleeve 1 is provided with an annular flange or extension 5, within which a seat 6 is provided for the edge of a cap or closure 7. This cap or closure is made with a concavity to provide for a portion of the head of the bolt and to form a suitable clearance 8 for said head,—said head being made of rounded or spherical form.

The annular extension 5 is provided interiorly near its free edge with segmental shoulders 9 and a head or locking member 10 is disposed over said annular extension and provided with a flange 11 which enters the latter and is formed with lateral lugs 12 adapted to engage behind the segmental shoulders 9 when the parts are in locking position and at one end of each of said

lugs, a shoulder 13 is formed to engage end portions of the shoulders 9 and limit the turning movement of the head 10. The head 10 overlies the end of the bearing sleeve extension 5 and is provided interiorly with cams 14 to coöperate with cams 15 upon the cap or closure 7 so that when the head 10 is turned, the cap or closure will be pressed against its seat 6 and the bearing sleeve. The cap 7 is provided near its bearing edge with segmental shoulders or lugs 16 and the bearing sleeve extension is provided with segmental shoulders 17 so that when the head 10 is turned, the cap 7 will also be turned somewhat so as to cause the lugs 16 or shoulders 17 to become disposed behind the shoulders 17 and if desired said lugs 16 may be provided with shoulders similar to the shoulders 13 so as to limit the turning movement of said cap.

With our improvements the cap or closure will be normally clamped tightly to its seat on the bearing sleeve and it is apparent that by a slight turning of the parts the cap and its locking means will be released and may be quickly removed to permit access to the head of the bolt for testing purposes.

Having fully described our invention what we claim as new and desire to secure by Letters-Patent, is:

1. In a staybolt structure, the combination with a bearing member for a staybolt, said bearing member having an annular extension provided interiorly with two sets of segmental shoulders disposed in different planes, of a cap or closure adapted to seat against the bearing member and having lugs to engage behind one of said sets of segmental shoulders, and a head having a part to enter said annular extension and having lugs to engage behind the other set of segmental shoulders in said annular extension.

2. In a staybolt structure, the combination with a bearing member for a staybolt and having an annular flange or extension provided interiorly with two sets of annular shoulders disposed in different planes, of a head having a part entering said annular extension and provided with lugs to engage behind one set of segmental shoulders, a cap or closure seated on the bearing member and entering said head, said cap or closure having lugs to engage behind the other set of segmental shoulders, and cams between said cap or closure and the head.

3. In a staybolt structure, the combination with a bearing member of a staybolt, said bearing member provided with an annular extension having two sets of internal segmental shoulders, of a cap or closure seated within said extension and having lugs to engage behind one set of segmental shoulders, a head provided with a part entering the annular extension and having lugs to engage behind the other set of segmental

shoulders, and stop means for limiting the turning movement of said parts.

In testimony whereof we have signed this specification in the presence of two subscribing witnesses.

JOHN ROGERS FLANNERY.
ETHAN I. DODDS.
